UNITED STATES PATENT OFFICE.

JOHN H. KEETLE, OF ASHLAND, NEBRASKA.

ROAD-GRADING MACHINE.

1,211,167.

Specification of Letters Patent.

Patented Jan. 2, 1917.

Application filed June 10, 1916. Serial No. 102,921.

To all whom it may concern:

Be it known that I, JOHN H. KEETLE, a citizen of the United States, residing at Ashland, in the county of Saunders and 5 State of Nebraska, have invented or discovered certain new and useful Improvements in Road-Grading Machines, of which the following is a specification, reference being had therein to the accompanying drawings.

10 This invention relates to road working or road grading machines for rounding up and smoothing dirt roads, and has for its object to provide a convenient machine adapted to work both sides of the road at 15 the same time, the machine being of such construction that the draft animals or motor may travel in the middle of the road where it is hardest, while side draft will be avoided, in that drag of the scrapers at 20 the opposite sides of the machine will be balanced. The main scrapers are carried by frames which have hinged connections with a main or central frame, so that the said scrapers may be adjusted to any desired 25 drooping positions relative to said main frame in rounding up the road, the said hinged frames being adapted to be lifted up to vertical positions, or nearly so, so as to be folded in toward the main frame when it 30 is desired to cross narrow bridges and avoid interference with the side walls or side railings thereof. Means are provided for adjusting the main scrapers in and out of their main frames and for changing the inclinations 35 of their working positions, all as will hereinafter more fully appear.

In the accompanying drawings Figure 1 is a plan view of the improved machine. Figs. 2 and 3 are side and end views, respectively, of the machine, Fig. 4 is a detail view of the means for adjusting the main scrapers in and out, and Fig. 5 is a detail view of the means for varying the inclined working position of said main scrapers.

45 Referring to the drawings, the main frame of the machine consists of longitudinal bars 12 and cross bars 13 properly secured together, the ends of said cross bars overhanging said longitudinal bars. Bolted 50 to the forward end of the longitudinal bars is a plate or disk 14 to which is secured, by means of a king bolt 15, a similar plate or disk 16 carrying depending bars 17 through which passes a rod 18 on which the front 55 wheels 19 are suitably journaled. Pivots mounted on the rod 18 is a two-part yoke

or clevis 20 to which the draft pole or tongue 21 is suitably secured. By virtue of this construction the front wheels may be turned beneath the main frame of the machine to any desired positions in making short turns, or the draft tongue or pole may be turned entirely around beneath the machine, if desired, for compactness and convenience in shipping. 60 65

Depending from the rear ends of the longitudinal bars 12 are hangers 22 supporting a rod or axle 23 carrying a roller 24. The roller 24 is preferably made in two parts, as shown. At the extreme rear ends of the 70 bars 12 is a cross bar 24 provided with a yoke or clevis 25 for the attachment of a tongue or pole 26 of a two-wheeled push-gig or cart to be drawn by animals which may thus assist in the propulsion of the machine, 75 from the rear, if desired. The rear end of the main frame will preferably also be stiffened by additional cross bars 27 secured thereto.

Hinged to the overhanging ends of the 80 cross bars 13 are two side frames 28 carrying the main scrapers 29 which are pivotally mounted on bars 30 adjustable in and out by means of screws 31 suitably mounted in portions of the said side frames 28 and passing 85 through nuts in said bars 30. The screws 31 are provided at their inner ends with bevel gears 32. The bevel gears on the rear screws 31 mesh with crown gears 33 attached to vertical rods 34 suitably mounted in the 90 frames 28 and provided at their upper ends with hand wheels 35 by which they may be turned. Meshing with the said crown gears 33 are bevel gears 36 at the rear ends of longitudinal rods 37 which are provided at 95 their forward ends with bevel gears 38 meshing with the bevel gears 32 at the inner ends of the forward screws 31. By virtue of this construction in which the bars 30 are each provided with two separated nuts 100 through which the screws 31 pass, said bars may be given an in and out adjustment, parallel to the rods 37, by turning the hand wheels 35, so as to adjust the scrapers 29 to any desired lateral positions relative to the 105 main frame, according to the width of the road being worked.

The pivotal supports of the main scrapers 29 pass through spacing devices arranged between the tops of said scrapers and the 110 bars 30 by which they are carried, each of said spacing devices preferably consisting

of two metal disks 39 between which is a block of wood 40 somewhat wedge-shaped and preferably formed thicker at its front than at its back, so as to give an inclined mounting, relative to a horizontal plane, to the scrapers, so that they will work more efficiently in drawing in the dirt from the inclined sides of the road toward the center of the road.

10 The main scrapers work in inclined positions relative to the direction of movement of the machine, and, for the purpose of varying the inclined positions of the said scrapers, chains 41 are connected to the same near their outer ends, said chains passing inward through guides 41^a and around vertical winding spools or drums 42 mounted on rods 42^a provided with hand wheels 43 by which they may be turned. The rods 42 are also provided with detent wheels 44 which may be held in any desired positions, after the scrapers have been adjusted, by detent pawls 45. For adjusting one of the scrapers, to vary the inclination of its working face, one of the hand wheels 43 on one of the pivoted frames will be turned to let off one of the chains 41, and the other hand wheel will be turned to correspondingly tighten the other chain; and when the 30 scraper is adjusted to its desired inclined position it will be retained in such position by the chains 41 which at such time, will be drawn taut.

Supported by the cross bars 13 of the 35 main frame are U-shaped standards 46 joined together at their tops, longitudinally of the machine, by rods 47, and mounted in the vertical portions of said standards are winding rollers 48 provided with hand 40 wheels 49 by which they may be turned, for the purpose of winding up or letting off chains 50 each of which is attached at 51 to an outer portion of a hinged frame 28. From the point 51 each chain 50 passes to and 45 around a pulley 52 mounted in a pulley block 53 supported by one of the rods 47, the chain passing from said pulley 52 to a pulley 54 mounted near the outer end of the hinged frame 28, and running from said 50 pulley 54 to a pulley 55 in the said pulley block 53, and thence to and around a winding roller 48. The chains 50 thus serve to support the hinged frames 28 in any desired positions, which may be varied by letting off or drawing up the said chains 50 by 55 turning the hand wheels 49; and when the hinged frames have been adjusted to desired positions the winding rollers will be prevented from turning by means of detent hooks 60 49^a engaging the hand-wheels 49. The chains 50 not only serve to support the hinged frames in any desired working positions, but by means of said chains and the winding rollers 48 the said hinged frames 65 may be drawn upward and inward to nearly

vertical positions, as denoted in dotted lines at the left of Fig. 3, when it is desired to cross narrow bridges not affording sufficient space between the guards or side rails thereof for the passage of the machine when the 70 hinged frames are in their working positions.

The forward ends of the hinged frames 28 are connected to the forward ends of the longitudinal bars 12 of the main frame by 75 means of guy chains 28^a extending from said bars to the outer sides of the forward ends of the said pivoted frames, said chains serving to prevent side strain which would otherwise come on the hinges or pivotal points of 80 the said frames. The main frame will preferably be provided at its front end with a suitable seat 56 for the driver, and will also preferably be provided with supplemental scrapers 57 for leveling the middle of the 85 road and which may or may not be adjustably mounted.

Instead of locking the wheels 49 on the winding rollers 48 by means of the hooks 49^a, 90 flexible brake-bands 58, having end loops 59, may be passed around said wheels or rollers and the said loops may then be brought into such positions that the driver, occupying the seat 56, may insert his feet in said loops, and thus be able to tighten or slacken said 95 brake bands to hold said wheels and rollers stationary, or let off the chains wound on said rollers, in letting down the pivoted frame 28. Also, if desired, these brake bands may be utilized to hold up the said pivoted frames, when lifted, as denoted in dotted 100 lines in Fig. 3.

From the foregoing it will be understood that the invention provides a convenient road machine by which both sides of the 105 road may be worked at the same time, and which is adapted, owing to the various adjustments referred to, for working roads of different widths and in any desired manner, according to the resistance afforded by the 110 material being worked.

Having thus described my invention I claim and desire to secure by Letters Patent:

1. In a road machine, the combination with a main frame, of side frames extending longitudinally of and parallel to said main frame and to each other, and having hinged connections with said main frame, scrapers carried by said hinged side frames, means for adjusting said scrapers bodily in and out on said hinged side frames, a support extending upward from said main frame, winding rollers mounted in said support, flexible connections passing from said winding rollers to the outer parts of said hinged frames, suitable pulleys over which said flexible connections run, means for turning said winding rollers and means for retaining said rollers in any desired positions.

2. In a road machine, the combination 130

- with a main frame, of side frames extending longitudinally of and arranged parallel to said main frame and to each other, and having hinged connections with said main 5 frame, said side frames being adapted to be lifted nearly to vertical positions, scrapers carried by said hinged side frames, means for adjusting said scrapers bodily in and out on said side frames, a support extending upward from said main frame, winding rollers mounted in said support, flexible connections passing from said winding rollers to the outer parts of said hinged frames, suitable pulleys near the top of said support and 10 over which said flexible connections run, means for turning said winding rollers and means for retaining said rollers in any desired positions; whereby said hinged frames may be lowered to bring said scrapers into 15 working positions and may be raised so as that their outer ends are brought up near the top of said support for compactness in traveling the machine through narrow passageways.
- 20 3. In a road machine, the combination with a main central frame, of side frames extending longitudinally of and arranged parallel to said main frame and to each other and having hinged connections with 25 said main central frame so that they may be raised and lowered, scrapers carried by said hinged frames, means for raising and lowering said hinged frames for the purpose of varying the vertical working positions of 30 said scrapers or for lifting said hinged frames nearly to vertical positions, to narrow the machine, when desired, and means for adjusting said scrapers in and out on said hinged frames, said means comprising 35 carrying bars for said scrapers, said bars being each provided with two separated nuts, adjusting screws passing through said nuts, and hand-operable gearing for turning 40 said screws.
- 45 4. In a road machine, the combination with a main central frame, of side frames having hinged connections with said main central frame so that they may be raised and lowered, an adjustable bar on each of said 50 hinged frames, said bars being each pro-
- vided with two separated nuts, scrapers pivotally supported on said bars so that they may be turned to different inclined positions, a screw passing through each of said nuts and provided with a gear, an adjusting 55 shaft mounted on each hinged frame and having at its upper end a hand wheel by which it may be turned and having at its lower end a gear meshing with the gear on one of said screws, a longitudinal rod mounted in each hinged frame and having at one end a gear meshing with the gear on said adjusting shaft, and having at its other end a gear meshing with the gear on the other of said screws, so that by turning said adjusting shaft the bars carrying said scrapers may be moved in and out with a parallel adjustment by the screws passing through the two separated nuts in each of said bars. 60
5. In a road machine, the combination 70 with a main central frame, of side frames having hinged connections with said main central frame so that they may be raised and lowered, an adjustable bar on each of said hinged frames, said bars being each pro- 75
- vided with two separated nuts, scrapers pivotally supported on said bars so that they may be turned to different inclined positions, a screw passing through each of said nuts and provided with a gear, an adjusting 80 shaft mounted on each hinged frame and having at its upper end a hand wheel by which it may be turned and having at its lower end a gear meshing with the gear on one of said screws, a longitudinal rod mounted 85 in each hinged frame and having at one end a gear meshing with the gear on said adjusting shaft, and having at its other end a gear meshing with the gear on the other of said screws, so that by turning said adjusting 90 shaft the bars carrying said scrapers may be moved in and out with a parallel adjustment by the screws passing through two separated nuts in each of said bars, and means for adjusting said scrapers on their 95 pivots in said bars, to vary the inclination of their working positions.

In testimony whereof I affix my signature.

JOHN H. KEETLE.
